UNITED STATES PATENT OFFICE

GEORGES WILMET, OF NEW YORK, N. Y., ASSIGNOR TO ARMSTRONG CORK COMPANY, OF LANCASTER, PENNSYLVANIA, A CORPORATION OF PENNSYLVANIA

DESIGN FOR A CONTAINER CAP

Application filed January 16, 1933. Serial No. 46,861. Term of patent 7 years.

To all whom it may concern:

Be it known that I, GEORGES WILMET, a citizen of Belgium, residing at New York city, county of New York, State of New York, have invented a certain new, original, and ornamental Design for Container Caps, of which the following is a specification, reference being had to the accompanying drawing, forming a part thereof, and of which—

I claim:

The ornamental design for a container cap as shown.

GEORGES WILMET.
